TARGET RANGE

Albert G. Varrelman, Vineland, N. J.

Application June 3, 1933, Serial No. 674,254
Renewed June 18, 1934

2 Claims. (Cl. 124—15)

This invention relates to a device for use as a target range, the general object of the invention being to provide a frame having its front open, with means for supporting a strip of paper or the like, having targets thereon, within the frame so that the targets will appear in succession in rear of the opening as the strip is moved step by step in the casing.

Another object of the invention is to provide means for moving the strip so as to bring the target in position where it can be seen through the opening in the casing, with means for supporting the target in stretched position and also to provide means for illuminating the target.

15 A further object of the invention is to provide a verification strip in rear of the target strip and supported for movement relative thereto.

This invention also consists in certain other features of construction and in the combination 20 and arrangement of the several parts, to be hereinafter fully described, illustrated in the accompanying drawings and specifically pointed out in the appended claims.

In describing the invention in detail, reference 25 will be had to the accompanying drawings wherein like characters denote like or corresponding parts throughout the several views, and in which:—

Figure 1 is a side view of the invention.

30 Figure 2 is a face view of a portion of the target strip, showing one of the targets thereon and also showing a portion of the verification strip in rear of the target strip.

Figure 3 is a detail view showing how one of the 35 trunnions of one of the rollers is supported.

Figure 4 is a front view showing the supporting means for the verification strip and said strip.

Figure 5 is a detail sectional view showing the supporting means for the lower guiding roller and 40 the knife.

Figure 6 is a horizontal sectional view through a portion of the casing.

Figure 7 is a view of the bracket and the carrying roller for the target strip and the upper guide 45 roller.

Figure 8 is an end view of said bracket and showing how the trunnions of the two rollers are supported thereby.

Figure 9 is a view of one of the weighted shafts 50 with the rubber roller thereon and also showing the bracket for supporting the shaft.

Figure 10 is a view taken at right angles to Figure 9.

In these drawings, the numeral 1 indicates a 55 supporting frame for a casing 2, said frame in-

cluding the legs 3 and the braces 4. The front of the casing 2 is open and is closed by a door 5 hinged to the frame 1, as shown at 6, and having an opening therein to expose the targets. The rear of the casing slopes upwardly and forwardly, as shown in Figure 1, and a bullet-proof plate 7 is detachably connected to the rear wall of the casing, such as by means of the bolts 8. Flanges 9 are connected to the internal side walls of the casing an appreciable distance in front of the rear wall and these flanges have inwardly and rearwardly extending portions 9', these parts acting to prevent any bullets striking the armor plate 7 from rebounding through the target or through the opening in the front of the casing. These flanges will cause any bullets striking them to drop down into the rear portion of the bottom of the casing which may contain sand. Thus the bullets fired at the targets can be reclaimed.

A pair of brackets 10 is arranged in the upper 75 part of the casing, one adjacent each side thereof and each bracket is of channel shape in cross section, with its bight lowermost and the rear end of each bracket has its bight portion extended and curved upwardly, as shown at 11, 80 to provide a support for the trunnions or ends of the shaft 12 which supports the rolled strip 13 of paper or other suitable material and on which the targets 14 are placed in spaced relation and in a longitudinal row, as shown in Figure 2. One of the flanges of each bracket 10 is formed with a notch 15 for receiving an end or trunnion 16 of a guide roller 17 which is placed forwardly of the shaft 12 and over which the target strip passes as it leaves the roller. 85 The strip passes downwardly on this guiding roller 17 to a second guiding roller 18 placed in the lower part of the casing and this roller 18 is carried by an elongated bracket 19 of angle shape in cross section, with one limb arranged 90 horizontally and having its forward edge beveled to provide a knife 20, as shown in Figure 5. The ends of this bracket 19 are bent at right angles, as shown at 19', and these ends are pivoted to a pair of plates 21, as shown at 22, and 95 one end of each plate is pivotally supported by a side wall of the casing, as shown at 23.

Thus the bracket 19 can be swung forwardly to facilitate the strip of paper or the like being placed on the guide roller 18, and then the 105 bracket is moved to the position it occupies in Figure 1.

From this guide roller 18, the strip passes to a second roller 24 rotatably supported on the bottom of the casing, adjacent the front there- 110

of, and this roller 24 is rotated from the motor M through means of the gearing 25.

It will, of course, be understood that if desired, the roller 24 can be turned by hand and 5 in order to permit this, I provide a spring pressed bearing member 26 having a socket therein for receiving one end of the shaft 27 of said roller, said bearing member having a non-circular projecting part 28 for receiving a crank handle.

10 I also provide upper and lower brackets 29 adjacent each side of the casing, each bracket forming a bearing for a shaft 30 of the shape shown in Figures 9 and 10. A crank part 31 of each shaft carries a rubber roller 32 grooved and 15 toothed, as shown in Figures 9 and 10, for engaging the side of the strip, with the other end of the shaft bent to extend at right angles and provided with a weight 33 which is adjustably arranged on the shaft by means of the nuts 20 34. Thus these weights will hold the shafts with the rollers 32 against the side portions of the strip, as shown in Figure 1, so as to hold the strip straight as it passes from the roller 17 to the roller 18. The weights can be adjusted 25 to properly hold the strip and by swinging the weighted parts upwardly, the rollers can be moved out of contact with the strip to facilitate the placing of the strip in the device.

A verification strip 35 is carried by a roller 30 40 journaled in the brackets 41 arranged under the brackets 10 and this strip extends downwardly and rearwardly over a guide roller 42 adjacent the bottom of the casing and is then wound upon a roller 43 which may be driven 35 from the motor M by the gearing 44. This strip 35 is much narrower than the main strip 13, as shown in Figure 2.

Thus it will be seen that the target carrying strip can be moved to a position where a target 40 thereon will be centrally arranged in rear of the front opening so that it can be fired at and bullets passing through the target will also pass through the strip 35 so that this strip will record the shots and provide a check-up for the target 45 strip. It will, of course, be understood that in order for this verification strip to provide a check-up and record of the shots passing through the target strip, the verification strip must be moving while the target strip is stationary and 50 shots are being fired at the target thereon. Any suitable means may be used for moving the target strip and the verification strip and if the motor is used, suitable connections must be provided for moving the target strip to position a 55 new target thereon where the target can be fired at, after which the target strip remains stationary while the verification strip is moved as the target is being fired at in order that the 60 shots will make a record on the verification strip.

Lamps 45 are placed in a reflector 46 for illuminating the targets.

This range is designed suitably for all targets used in any recognized pistol match, also for instructing beginners. It is suitable for indoor use, having the necessary light for the proper lighting of a target indoors. It is also weather-proof so that it may be used outdoors. This range is also portable in that it may be taken apart 70 and re-assembled wherever desired. It is also complete in itself in that it does not need any frames, supports or backing for the target to be shot at. It also makes it possible to have the target (that is, the bull's-eye) in the same position at all times, thereby being a great help to

the shooter in that his aiming point is always in the same place. This range will also expedite the shooting in that after the target is shot at, it may be pulled down and torn off or rolled up on either a hand cranked or motorized roll, for the reason that when one target is pulled down, another is immediately in place, being fed from the roll above. This range also catches all spent bullets in a sand trap, and they can be reclaimed. It also prevents any ricochets from doing any damage after striking the back plate.

80 The sand may be placed in a drawer 47, shown in Figure 1, and this drawer can be removed through an opening in the rear of the casing, the opening being covered by a door 48.

85 The weight of the bracket 19 and roller 18 presses the target strip against a portion of an upright plate 49 in the lower part of the casing and this acts to hold the strip taut and by swinging the bracket forwardly, the strip can be readily passed under the roller 18.

90 It is thought from the foregoing description that the advantages and novel features of the invention will be readily apparent.

95 It is to be understood that changes may be made in the construction and in the combination and arrangement of the several parts, provided that such changes fall within the scope of the appended claims.

100 What is claimed is:—

105 1. A device of the class described comprising a casing having an opening in its front, a strip having a longitudinally extending row of targets thereon, a roller upon which the strip is wound, means for rotatably supporting the roller in the upper part of the casing, a receiving roller in the lower part of the casing, guiding rollers for guiding the strip from the first roller to the second roller in a vertical path, weighted rubber covered rollers for engaging the side portions of the strip for holding the same straight as it passes from one guide roller to the other, a bullet-proof plate in the rear of the casing, flange members in each side of the casing adjacent the side edges of the plate, a sand trap in the bottom of the casing at the rear thereof, means for illuminating the targets, a verification strip, an upper roller carrying the same, a lower roller upon which the said strip is wound, a guiding roller for the verification strip located between the last mentioned upper and lower rollers, said last mentioned upper and lower rollers and the last mentioned guiding roller supporting a portion of the verification strip in rear of the vertical portion of the target strip, and means for turning the last mentioned lower roller for imparting movement to the verification strip while the target strip is stationary and is being shot at.

110 2. A device of the class described comprising a casing having an opening in its front, a strip having a longitudinally extending row of targets thereon, a roller upon which the strip is wound, means for rotatably supporting the roller in the upper part of the casing, a vertically arranged plate extending transversely across the lower part of the casing, a bracket hingedly supported in the casing adjacent the plate and holding a portion of the strip between itself and said plate, said bracket having a beveled edge for severing one portion of the strip from the portion clamped between the bracket and the plate, guiding means for guiding the strip from the roller to the clamping means in a vertical path, weighted rubber covered rollers for engaging the side portions of the strip, for holding the same straight as it

passes from the roller to the clamping means, a bullet-proof plate in the rear of the casing, flanged members in each side of the casing adjacent the side edges of the bullet-proof plate, 5 a sand trap at the bottom of the casing at the rear thereof, a verification strip, a roller located in the casing and carrying the verification strip, guiding means for the verification strip for guid-

ing the same in rear of the vertical portion of the target strip and across the path of the bullets passing through said target strip, and means for imparting movement to the verification strip while the target strip is stationary and is being shot at. 80
